US00D622690S

(12) **United States Design Patent**
Kwon et al.

(10) **Patent No.:** **US D622,690 S**
(45) **Date of Patent:** **** Aug. 31, 2010**

(54) **MOBILE PHONE**

(75) Inventors: **Kyung-Jun Kwon**, Hanam-si (KR);
Sang-Min Hyun, Seoul (KR); **Nam-Mi Kim**, Seoul (KR)

(73) Assignee: **Samsung Electronics Co., Ltd.**,
Suwon-si (KR)

(**) Term: **14 Years**

(21) Appl. No.: **29/351,019**

(22) Filed: **Nov. 27, 2009**

(30) **Foreign Application Priority Data**

Oct. 22, 2009 (KR) 30-2009-0046470

(51) **LOC (9) Cl.** **14-03**

(52) **U.S. Cl.** ..... **D14/138 AD**

(58) **Field of Classification Search** ..... D14/138 R,
D14/138 AD, 138 AC, 138 C, 138 G, 191,
D14/203.1–203.8, 496, 138 AA, 138 AB,
D14/247–248, 137, 147, 218, 341–347; D10/65,
D10/78, 104; D13/168; D18/7; 455/566,
455/575.1, 575.3

See application file for complete search history.
